ISADORE LESSON, ALSO KNOWN AS ISADORE L. LESAVOY, OF BROOKLYN, NEW YORK.

APPAREL.

Application filed April 14, 1927, Serial No. 183,861, and in Canada October 26, 1926.

This invention relates to bifurcated apparel garments, such, for instance, as a pair of underwear bloomers or bathing trunks, or the drawers portion of a union suit, or of a 5 "one piece" bathing suit, or a pair of pajama trousers, &c.; wherein (1) these apparel units are composed of a pair of sections, each section having, from the waist down, a rear edge having an upper portion, 10 an intermediate curved portion and a lower portion, each section also having a front edge portion opposite said lower portion of the rear edge, and wherein (2) said curved portions of the two sections are stitched together to form a central or crotch seam, and on each section said lower portion of the 15 rear edge and said front edge portion are to be stitched together to form a leg seam, such leg seams joining said central seam at 20 a common point.

The improvement offered by the present invention, as will be explained, is attained whether each of said sections includes one or 25 more pieces of fabric, and is also attained whether each section is cut as a separate member or both sections are cut to form parts of a single piece of fabric.

The invention provides an apparel unit as hereinabove described, hereinafter called a 30 garment, which shall be self-reinforcing across the seat, due to the automatic creation, on the occurrence of a cross-crotch pull, of an elongate bundling of the seat material across the crotch distinctly centralized some distance to the rear of said seam intersection point.

This is attained by relating in a novel 35 way the various edge portions above mentioned, and a straight of the goods from 40 which the sections are cut.

In the drawings,

Figure 1 is a fragmentary view showing some of such relations;

Figure 2 shows on a slightly reduced scale 45 a pair of separate sections for making a pair of bloomers,—parts between dot and dash lines of Figure 2 corresponding to the parts of Figure 1;

Figure 3 is a view similar to Figure 2, 50 showing the said two bloomer sections cut from a single piece;

Figure 4 indicates modifications, the full 55 lines bounding sections for making pajamas;

Figure 5 is a view showing on an enlarged 60 scale a section of Figure 2;

Figure 6 is a fragmentary front perspective showing a typical crotch-adjacent garment structure;

Figure 7 is a similar perspective view looking toward the right in Figure 6; 60

Figure 8 is a view similar to Figure 7, showing the elongate bundling;

Figure 9 is a diagrammatic transverse section of the bundling.

Referring to Figure 5, the section shown 65 has, in common with the corresponding sections of Figures 1 to 4, a rear edge from the waist line down, (which waist line may be shaped as desired, for instance as indicated at 18, if it be the upper boundary of the garment), composed of an upper portion 11^b, an intermediate curved portion 11^a, and a lower portion 13. The upper end of said lower portion meets the lower end of the curved portion at a point 14. The section also 70 has a front edge composed of a lower portion 13', and an upper portion 15; these portions meeting at a point 17, just below a slight flaring 20 preferably present, to facilitate seaming together the edge portions 13 and 13' as well as to help in maintaining a decided character for point 75 17 after seaming. Seaming together said edges 13 and 13' makes the leg seam for one of the sections, while seaming the corresponding edge portions 12 and 12' of the companion section makes the other leg seam. Then, when the central or crotch seam is 80 made as just described, the two leg seams will both meet the crotch seam at a common point, shown at 147 in Figure 6. This brings together the two sets of points 14 and 17 (the notch 16 of Figure 3 corresponding to the flares indicated at 20 in Figure 5), so that the leg seams are located 85 at 123 and 123', and the crotch seam at 111, in Figures 6, 7 and 8.

The front seam 115, present if the sections of either of Figures 2 and 4 are used, is 90 made by joining the edges 15 of the sections. However, when the finished garment is to be say a pair of pajamas, the front seam 115 need not be present, at least along the entire lengths of edges 15; for instance, the seam 115 may run up only as far as the 95 broken line 115' of Figure 6, and the edges 15 above such line finished separately.

The broken lines of Figures 2, 3 and 4 are 100 merely to indicate that the sections need not be unitary within the full lines, but may be 110

made of several pieces seamed together, or partly together and partly separately, to provide doffing and donning plackets, say along said broken lines. The broken lines marking off upper extensions of the sections of Figure 4 are merely to indicate that the garment may be upwardly extended to form a union suit or the like.

In other words, the principles of the invention go beyond the mere showing of Figure 5, which is only illustrative of the invention as applied to making women's bloomers; and consequently the lower end 14' of the lower portion 13 of the rear edge, is shown as having a co-terminus with bottom edge 19 which, in the finished garment, if such be a bloomer, encircles the knee preferably with such fullness as to permit the application of an elastic tape for gathering the lower end of the bloomer leg yieldingly around the leg of the body.

Figure 5 shows most clearly the chief novelty of the invention, as well as preferable characteristics of the cut of each section, as to shapes and relations of edge portions 11^b, 11^a and 13 for the rear of the garment and of edge portion 13' at the front, and the relations of such edge portions to a straight of the goods; such straights being indicated by the lines forming the criss-cross hatched areas of Figure 5. A straight of the goods, consequently, thus runs along line 25.

Preferably, the intermediate curved edge portion 11^a is substantially an arc of a circle, so that line 23, substantially equal to either of lines 21 and 22, parallel to the straights of the goods, may be said to represent the radius on which the curve is struck; line 24, tangent to the curve near its lower end, is almost perpendicular to the upper edge of edge 13; the upper portion 11^b of the rear edge is a straight line continuation of the straight of the goods indicated by line 25; the true or full bias of the goods is indicated by the line 26; broken line 27 is perpendicular to line 26; and, where the garment to be made is an adult woman's bloomer line 21 represents approximately one-fifth the length of the line 14—17, and line 22 represents roughly one-third the length of line 125.

The essentials are:

That, whether or not the lower portion 13 of the rear edge of the section has a lower terminus at the knee point (14' of Figure 5), or below the knee point as in the case of pajamas as indicated in Figure 4, (a) said terminus is so located that the same is offset, in a direction perpendicular to the straight of the goods indicated by the line 125, from the lower end 11^c of the upper portion 11^b, by at least approximately one-sixth the offset, in the same direction, of the upper end 14 of said lower portion, from said lower end 11^c of said upper portion; and (b) these

various edge portions are so proportioned and relatively arranged that when the garment is finished, a line of pull, across the seat of the garment, will meet the curved portion 11^a intermediate its ends and at a point, as the point X, where such curve is cut on an appreciable bias, as would be the case were the line 31^a assumed to represent such line of pull. A relative offset, as to the lower and upper ends of said lower portion of the rear edge of each section, in regard to the lower end 11^c of the upper edge portion 11^b, as just described, that is, where the relation is say 6 inches to one inch, gives a fairly satisfactory bundling effect; but a very good bundling effect is obtained when the relative offset is such that the relation is six inches to four inches or even possibly a little more, while the ideal bundling effect is apparently obtained when the relation is six inches to three inches.

The bundling effect just referred to is illustrated very clearly in Figures 8 and 9. When a garment made according to the invention is subjected to a pulling strain across the seat, as indicated by the arrows 31 of Figure 7, the seat material 30 automatically rediscloses itself to form a distinctly centralized elongate bundling as indicated at 32 in Figure 8. This bundling is a rope-like reinforcement automatically temporarily made; and apparently always having the peculiarity indicated in Figure 9. The two plies 32^a hook over and under, to bring the double-ply edge portion 32^b toward or even against the seat material at the point 32^c, in the latter case sometimes even to hook under the edge portion 32^b and point the latter toward the "roots" 32^d of the plies 32^a. In operation, the bundling 32 increases in transverse compactness and hook-over, and in surprising strength, the greater the intensity of the pull along its length. In this connection, note that where the curved portion 11^a is circularly curved, as preferred, the same, in that subdivision thereof extending upwardly from the upper end of line 31^a, to the lower end 11^c of upper portion 11^b, progressively increases its degree of inclination to the straight of the goods indicated by the line 14—17; so that, if the intensity of the cross-crotch pull increases, there is an increase in bundling intensity, at a rate which may be loosely described as corresponding to a geometric proportion, which probably explains the extraordinary strength of the rope-like reinforcement across the seat on the occurrence of a cross-crotch strain which would readily rupture the ordinary garment at a point of seam intersection even where expensively reinforced with many gussets. Nor does it seem to make any difference, in the case of the present invention, when but a single fairly weak thread is used to sew the various seams.

The relative dimensions and edge shapings described in connection with Figure 5 are desirably modified to permit well known principles of the cutter's art to be applied 5 after settling on the sex, age and degree of stoutness of the figure to be clothed; to provide a garment which when worn will be free from any noticeable bunching or binding anywhere, and to give maximum efficiency in the seat reinforcement according to 10 the invention.

It is recommended that edge portion 13 should not be made so concave that any part of a leg seam will touch or approach 15 the material adjacent to the line 31^a in manner to interfere with formation of bundling 32 on the occurrence of a cross-seat strain.

I claim:

1. A bifurcated apparel garment as described, including a pair of sections each having from waist to the bottom of the garment a rear edge composed of an upper edge portion (11^b), an intermediate edge portion (11^a) flared downwardly and outwardly to 25 include a concave curve, and a lower edge portion (13); said curved edge portions stitched together to form the crotch seam and said lower edge portion (13) of each section stitched to another edge portion 30 (13') thereon to form a leg seam on each section the lower end (14') as well as the upper end 14 of the lower edge portion (13) being offset in a direction (17—14) along a straight of the goods from the lower 35 end (11^c) of the upper edge portion (11^b), the lower end (14') of said lower edge portion (13) being thus offset at least approximately one-sixth as much as the upper end (14) of said lower edge portion (13), and 40 a point (x) on the intermediate curved edge portion (11^a), where such curve is cut on a bias to the goods, defining, with the lower end (14') of the lower edge portion (13), a straight line (31^a) containing a straight of 45 the goods; whereby in the finished garment a line of pull across the seat substantially perpendicular to the crotch seam will cause the seat material to form a hook-over bundling (32) extended in pull-strain-absorbing 50 position substantially perpendicular to the crotch seam (111).

2. A bifurcated apparel garment as described, including a pair of sections each having from waist to the bottom of the garment a rear edge composed of an upper edge portion (11^b), an intermediate edge portion (11^a) flared downwardly and outwardly to include a concave curve, and a lower edge portion (13); said curved edge portions

stitched together to form the crotch seam 60 and said lower edge portion (13) of each section stitched to another edge portion (13') thereon to form a leg seam; on each section the lower end (14') as well as the upper end 14 of the lower edge portion (13) being offset in a direction (17—14) 65 along a straight of the goods from the lower end (11^c) of the upper edge portion (11^b), the lower end (14') of said lower edge portion (13) being thus offset approximately 70 one-half as much as the upper end (14) of said lower edge portion (13), and the lower end (14') of the lower edge portion (13), together with a point (x) on the curve of the intermediate edge portion (11^a) where 75 such curve is cut on a bias to the straight of the goods, defining a straight line (31^a) containing a straight of the goods which will lie substantially parallel to a line of pull across the finished garment perpendicular 80 to the crotch-seam (111); whereby such pull will cause the seat material on the two sections to curl up on itself to form a hook-over bundling (32) extended in pull-strain-absorbing 85 position transverse to the crotch-seam (111) of the garment.

3. A garment according to claim 1, characterized by the fact that the intermediate curved portion (11^a) of the rear edge of each section is so shaped, and such sections 90 are so cut from the goods, that there is substantially a continuously progressive decrease of inclination, to the straight (125) of the goods running up and down the section, of the successive points establishing the 95 curved portion (11^a), along a subdivision thereof which runs upwardly toward the lower end (11^c) of the upper portion (11^b) of the rear edge from a point on such curved portion which lies near the upper terminus 100 (x) of said line of pull, whereby during intensification of said pulling stress said bundling (32) becomes wound into a more and more compact and a stronger and stronger rope-like reinforcement the more 105 the pulling stress is increased.

4. A garment according to claim 3, characterized by the fact that the lower portion (13) of the rear edge of each section is substantially straight between the knee-point 110 (14') of the finished garment and the upper end (14) of such lower portion (13), to prevent a leg seam on the finished garment from substantially hindering the setting up of said bundling.

ISADORE LESSON,
